STEAM HEATING SYSTEM

Filed March 10, 1923

FIG. 2.

UNITED STATES PATENT OFFICE.

BRUCE FORD, OF PHILADELPHIA, PENNSYLVANIA.

STEAM HEATING SYSTEM.

Application filed March 10, 1923. Serial No. 624,294.

The present invention relates to improvements in low pressure steam heating systems in which the water of condensation is returned to the boiler by gravity, and the principal object of the present invention is to provide for a supply of steam to the radiators, not only when the boiler temperature is appropriate for steam generation at or above atmospheric pressure, but also when 10 the temperature is below that for steam generation at atmospheric pressure, or in other words, the object is to provide heat at the radiators at times, or under conditions, when, without my improvement, they would 15 be cold, thus extending the range of usefulness or effectiveness of the system, both in respect to firing up or starting, and in respect to operation when the fire is low. Other objects of the invention will appear 20 from the following description:

Generally stated, this invention comprises the combination of; a vacuum pump connected to the return or air-line for insuring a higher water lever in an air-separating 25 column in the return piping than the water level of the boiler, even at steam pressures at or below atmospheric pressure, whereby steam may be generated and distributed at 30 abnormally low boiler temperature; float means for starting the pump; and float means responsive to increase in the difference 35 in these water levels for automatically stopping the pump and preventing the escape of water from the system. As a result, there are provided simple, safe and positive means of accomplishing the objects, with provision for the return to the boiler by gravity of the water of condensation.

The invention also comprises the improvement 40 to be presently described and finally claimed.

In the following description, reference will be made to the accompanying drawings, forming part hereof, and in which

Figure 1 is a diagrammatic and schematic view illustrating a steam heating system embodying features of the invention, and

Fig. 2 is a view illustrating one form of the many well-known types of snap-switch applicable to employment in connection with the invention.

In the drawings, 1 is a radiator, 2 its hand-valve and 3 its steam trap or thermostatic valve, which, as is well known, is automatically closed when steam is present and is automatically opened when water or air are

present. 4 is a steam generating boiler. 5 is a steam line, and 5^a risers therefrom to the radiators. 6 is an air and water return line having a water receiver at 7, which 60 separates air and water for the return of the latter by gravity through the pipe or connection 6^a to the boiler and for the controlled escape of the air from the system. As shown, the water column is contained by a 65 covered tank or vessel 7 and the pipe 6^a, and at its base communicates with the water in the boiler, and the difference in level between the water in the tank 7 and the water in the boiler is indicated by *a*. There is a 70 float device for limiting the difference in said water levels, thereby preventing overflow from the tank 7, and resulting escape of water from the system. The float device includes an air take-off comprising a passage or connection 8 having a float, actuated 75 valve 10, and there may be provided an air relief 9 with an inwardly closing check valve to exclude the atmosphere. 11 is a vacuum (or air exhaust) pump connected to the air 80 take-off 8 by a pipe 12, in which there is a check valve 13. The vacuum pump is shown as driven by an electric motor 14, and there are means responsive to, or directly or indirectly actuated by, the height of the water 85 column at 7 for stopping the pump. As shown, the valve 10 is opened and closed by the float 15^b and the circuit of the motor 14 is automatically opened and closed by the float 15^b. Evidently a snap-switch should 90 be employed for the automatic making and breaking of the motor circuit. One, but by no means an essential, form of such switch is shown in Fig. 2, in which 18 is an arm pivoted at 19 and pressed upon at one end 95 by a spring 20, adjustable by the adjusting screw 21. 22 are stops against which the spring 20 snaps the arm 18 as positions of rest. 23 is a contact lever also, but independently, pivoted at 19 and having a range 100 of motion in respect to the arm 18 by the provision of the adjusting screw 24, there being a spring 26^a between the arm and lever and a retarding spring 25 acting on the lever. The lever 23 opens and closes the 105 motor control circuit at *b*. The device so far described in connection with Fig. 2 is, assumed to be contained within a casing *c*, from which the arm 18 projects to be operated upon by the adjustable prongs 26 on the float shaft. 28 is a wet return that 110 communicates with the water of the boiler,

by way of a line 29. 30 are bleeder pipes for draining the water from the air-lines and in which there may be hand valves 33 and check valves 40, and 32 are bleeder pipes having check valves 41 for the steam lines, should steam condense therein. 31 are air relief pipes interposed between the steam and air lines and provided with steam traps 3^a of the kind described in connection with the radiators and shown at 3. These air relief and bleeder pipes may be placed in any parts of the system as may be desirable, or may be omitted when they are not necessary. It is presupposed that there is appropriate fire control apparatus for regulating the draft or dampers of the boiler fire as is customary.

The mode of operation may be described as follows:

20 In starting, the fire under the boiler is, of course, low and there is no steam in the system. The steam traps 3 are open, and the vacuum pump 11 is in operation. These conditions are favorable for the generation 25 of steam at lower pressure than that of the atmosphere. The vacuum pump will exhaust air from the entire system and tend to raise the height of the water column at 7 by causing water of condensation trapped in the radiators or in the return line 6 to be discharged into the water column and also, as the traps 3 begin to close against steam, by tending to suck water up from the wet returns 28 and the boiler, until the float 15^b is 30 raised sufficiently to open the motor control circuit at *b* and stop the vacuum pump, which will again be started when the float 15^b reaches a predetermined low level. When steam passes through the radiators 1 the 35 valves 3 close. The radiators are heated well in advance of the time when they would be heated if the vacuum pump were absent. As the fire comes up the pressure in the boiler rises, causing a tendency to back its water up the connection 6^a which together with the water of condensation coming by way of the air return line 6 raises the water level in the water column at 7 which in turn displaces air above it. The arrangement of the float is 40 such that the circuit is opened at *b* and the motor 14 is stopped before the valve 10 is closed. As the mixture of air and water of condensation from the return line reaches the water column it is separated, the air escaping by way of the valve 10, and the water 45 of condensation reaching the boiler by way of the connection 6^a by gravity. If the height of the water column materially diminishes the pump will be again started, and 50 will restore the level and the pump will be stopped. As the pressure in the boiler continues to rise until it exceeds atmospheric pressure by more than the value represented by the height *a*, the air will be expelled 55 through the check valve 9, the pump remain-

ing stopped. As the water column at 7 continues to rise the float 15^b closes the valve 10 before water escapes into the air take-off 8. Thus the difference in level *a* is kept substantially constant since the closing by valve 70 10 of the air take-off will prevent any substantial further rise in this direction, and lowering the water level will permit air to be exhausted through the check valve 9 by the opening of valve 10 and thus permit the 75 level of the water column at 7 to rise so long as the pressure at the top of the water column is above that of the atmosphere, and if the fire cools off and the pressure is reduced below that of the atmosphere and the float 15^b is lowered, the 80 vacuum pump is again started. A supply of steam at the radiators is insured in the manner above described. From the foregoing description it will be evident that the 85 vacuum pump and its connections and automatic control, by maintaining a difference in the pressure in the air line and that in the boiler (represented by the height *a*) in a direction favorable to the passage of steam to the radiators and water of condensation and air from the radiators through the traps 3 to the air return line 6, operate to provide heat at the radiators at times when otherwise the boiler pressure would be too low 90 to do so, and the check valves 9 and 13 oppose the reentry of air into the system.

The circuit of the motor 14 may be the main motor circuit, as illustrated for simplicity, or may, as often practiced, be a relay circuit for operating a main switch for starting and stopping the motor.

It should be understood that the rotary type of vacuum pump diagrammatically illustrated does not limit the invention to a pump of this type as any suitable means for applying vacuum may be substituted, and furthermore, a mechanical pump operated and controlled by an electric motor and its circuit is shown for the sake of simplicity 105 and clearness and not as limiting the invention beyond what is covered by the claims.

It will be obvious to those skilled in the art to which the invention relates that modifications may be made in details of construction and arrangement without departing from the spirit of the invention which is not limited in respect to those matters or otherwise than as the prior art and the appended 110 claims may require.

I claim:

1. In a steam heating system, the combination of a steam generating boiler, radiators, means for supplying steam from the boiler to the radiators, a water column whose base communicates with the water in the boiler, an air line and its connections from the radiators to the water column, traps for opposing the passage of steam 125 while permitting the passage of air and 130

water and included in the air line connections, an air take-off from the top of the water column, a vacuum pump operatively connected with the air take-off to apply 5 vacuum to and raise the water level of the water column above the water level of the boiler, and a float controlled mechanism for starting the pump in response to a low water level of the water column and stopping the 10 pump in response to a high water level of the water column.

2. In a steam heating system the combination of a boiler, a radiator, steam supply

means between the boiler and the radiator, an air return line connected to the radiator, 15 an air separating column connected to the air return line and boiler, a vacuum pump having valved connection with the top of the column, and mechanism connected with the pump for starting and stopping the 20 pump and responsive solely to conditions existing at the top of the column, said mechanism and pump constituting the sole means for controlling the water level in the column.

BRUCE FORD.
